UNITED STATES PATENT OFFICE.

JOSEPH GARAND, OF WOBURN, QUEBEC, CANADA.

HASP-LOCK.

1,171,037.

Specification of Letters Patent.

Patented Feb. 8, 1916.

Application filed April 5, 1915. Serial No. 19,129.

To all whom it may concern:

Be it known that I, JOSEPH GARAND, a subject of the King of Great Britain, residing at Woburn, Frontenac county, Province of Quebec, Canada, have invented certain new and useful Improvements in Hasp-Locks; and I do hereby declare that the following is a full, clear, and exact description of the invention, such as will enable others skilled in the art to which it appertains to make and use the same.

The object of my present invention is to provide a combination of a hook with a lock which is especially adapted to be used in connection with railway-cars, barns, sheds, &c.

It is an essential feature of my new construction, that it does not require any changes to be made on the door of the car, &c., and that my new hook, is used in exactly the same manner, as the old ones which were used hitherto, so that my new hooks can be substituted for the old ones without any trouble.

Another advantage of the new invention consists therein, that the lock, which is arranged slidably connected with my new hook, can be fixed at will either in inoperative position, allowing my new hook to be used just as an ordinary hook, or after clenching the hook the lock can be brought into a position, in which it locks the hook automatically, so that the door cannot be opened again but by the person who has the keys for unlocking the hook.

In order to more clearly disclose the construction, operation, and use of the invention, reference should be had to the accompanying drawings forming part of the present application.

Throughout the several figures of the drawings like reference characters designate the same parts.

In the drawings: Figure 1 shows a side elevation of my new hook with the lock being in unlocked position; and Fig. 2 shows the same parts in the position of being locked.

In the shown embodiment of my invention the shaft 1 has as usual at its one end an eye 2 and at its other end a hook 3 for securing it by a bolt at the one part and for clenching it on the other side into a staple fixed at the other part of a double-winged sliding door or at a door and its frame respectively. In its middle part the shaft 1 has at its upper side a wedge-shaped pro-

jection 4 opposite to this and at its lower side a notch 5 with inclined sides and behind it a small projection 6. The middle part of the shaft is inclosed in a flat casing, 60 consisting of two halves 7, 8 with flangelike lateral prolongations, which surround the shaft 1 and are kept together by clamp-rings 9, 10. Within the upper shell 7 there is hinged near to the circumference, at 11, 65 a two-armed lever one end of which is shaped so as to form a catch, while the other end of it is bent to the form of a trigger or latch 13. A spring-wire 14 wound around the pivot 11 and pressing with one 70 end from below against the latch 13, while abutting with its other end against the inner wall of the shell 7, keeps the catch 12 always pressed down on the shaft 1. Within the lower shell 8 there is hinged at 15 75 a two-armed member, one arm of which forms a hook or catch 16 fitting into the notch 5 of the shaft 1, (see Fig. 2) while the other arm 17 of said member is pressed upon by a flat spring 18, which is fixed at 80 19 at the outer circumference of the shell 8. A key can be introduced into the lock by the keyhole 20 near the bottom of shell 8, in order to unlock the lock and hook, and near to the pivot 15 there is arranged a lug 21 85 which limits the downward movement of the catch 16.

If my new hook and lock is in the position shown in Fig. 1, the catch 12, gripping behind the vertical edge of the wedge-shaped projection 4, keeps the casing 7, 8 with the lock in the unlocked position at the left side of the hook. If the point 3 of the hook is clenched into the staple 22 of the door or other part to be secured, then by 90 pressing on the latch 13 the catch 12 is released from the projection 4 whereupon the casing 7, 8 with the lock can be shifted to the right until the tongue 23 formed on the flange like lateral prolongation of the lower shell 8 strikes against the point 3. During this shifting movement of the lock the catch 16 passes over the small projection 6 and, owing to the pressure of the spring 18 on its counter-arm 17, the catch 100 105 110 115 120 125 130 135 on the plug 21 whereupon the projection 6 can pass the catch and the whole box 7, 8 with the locking tongue 23 can be reshifted to the left side (Fig. 1) which allows the 5 hook to be opened again.

It is thought that the construction, operation, and use of the invention will be clear from the preceding detailed description.

Changes may be made in the construction, 10 arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

1. In a combined hook and lock for doors 20 the combination of a shaft with an eye at one end and a hook on its other end; a shell slidably mounted on the shaft with a tongue-like projection extending on the shell along the shaft and adapted to engage 25 the point of the hook; means arranged on the shaft and on the inner side of the shell adapted to lock the shaft and shell together, when the tongue of the shell is in engagement with the point of the hook.
2. In a combined hook and lock for doors 30 the combination of a shaft with an eye at one end and a hook on its other end and a notch and a projection at the side of same in its middle part; a shell slidably mounted 35 on the middle part of the shaft; a tongue-like projection on the shell extending along the shaft and adapted to engage the point of the hook; a spring-pressed catch arranged within the shell and adapted to engage the notch at the side of the projection 40 in the middle part of the shaft, when the shell is shifted to that position in which its tongue-like projection engages the point of the hook.
3. In a combined hook and lock for doors 45 the combination of a shaft with an eye at one end and a hook on its other end; a shell

slidably mounted on the shaft; a tongue-like projection on the shell extending along the shaft, and adapted to engage the point 50 of the hook; means on the shaft and on the inner side of the shell, adapted to lock the shaft and shell together, when the shell is at the one end of the shaft where its tongue is in engagement with the point of the hook; 55 and other means on the shaft and on the inner side of the shell, adapted to lock the shaft and shell together, when the shell is at the opposite end of the shaft to that position in which the tongue engages the point 60 of the hook.

4. In a combined hook and lock for doors the combination of a shaft with an eye at one end and a hook at its other end; a shell 65 slidably mounted on the shaft and provided with a tongue like lateral projection adapted to engage with the point of the hook; a notch at the side of a projection on the middle part of the shaft within the shell; a two-armed member hinged within the shell, the 70 one catch-shaped arm of which is adapted to engage into the notch on the shaft, when the tongue on the shell engages with the point of the hook; a flat spring fixed within the shell and pressing on the other arm of 75 the two-armed member; a wedge-shaped projection on the shaft opposite to the aforementioned notch and projection; a two-armed lever hinged within the shell, with a catch-shaped arm, which is adapted 80 to engage behind the aforementioned wedge shaped projection of the shaft, and a latch-shaped arm which projects to outside of the shell; and a spring fixed within the shell, adapted to press the last mentioned catch-shaped arm down on the shaft; 85 substantially as described and illustrated.

In witness whereof I have hereunto set my hand in the presence of two witnesses.

JOSEPH GARAND.
